UNITED STATES PATENT OFFICE.

WILLIAM D. MOTT AND LEWIS VAN BROWN, OF ASHEVILLE, NORTH CAROLINA.

BURGLAR-ALARM.

1,256,504.

Specification of Letters Patent. Patented Feb. 12, 1918.

Application filed January 31, 1916. Serial No. 75,456.

To all whom it may concern:

Be it known that we, WILLIAM D. MOTT and LEWIS VAN BROWN, citizens of the United States, residing at Asheville, in the 5 county of Buncombe and State of North Carolina, have invented new and useful Improvements in Burglar-Alarms, of which the following is a specification.

This invention comprehends the provision 10 of a burglar alarm, primarily designed for use in connection with a movable member, such as a door, window, or the like, and constructed to automatically operate to sound an alarm when said movable member 15 is adjusted from its normal position.

In carrying out the invention we provide a means for rendering the alarm mechanism inoperative when desired, to permit the movable member to be opened and closed at will 20 without a sounding of the alarm.

The nature and advantages of the invention will be better understood as the following description is read in connection with the accompanying drawings, the invention 25 residing in the novel construction, combination and arrangement of parts as claimed.

In the drawings forming part of this application like numerals of reference indicate similar parts throughout the several 30 views and wherein:—

Figure 1 is a fragmentary sectional plan view of the door showing the device applied.

Fig. 2 is a front view partly broken away.

Fig. 3 is a section taken on line 3—3 of 35 Fig. 2.

Fig. 4 is a section taken on line 4—4 of Fig. 3.

Fig. 5 is a view similar to Fig. 1 showing a modified form.

Fig. 6 is a view similar to Fig. 2 showing 40 the modification.

Fig. 7 is a view showing in detail several elements of the mechanism.

Referring more particularly to the drawings 45 10 indicates generally an audible signal, preferably a bell of usual construction, wherein the alarm mechanism includes the escapement 11 with which the arm 12 of the hammer 13 is connected. The mechanism further includes an adjustable pintle 14 having 50 one end slidably fitted in the plate 15, and its opposite end projecting through the base 16 of the bell. The pintle 14 at a point in its length is provided with an enlargement 55 17 against which bears one end of an extensile spring 18, the opposite end bearing

against the plate 15 and operating to normally hold the enlargement 17 of the pintle disposed in the path of movement of the arm 12, in which position of parts the alarm 60 mechanism is rendered inoperative.

Secured to the base 16 is a limb 19 of a substantially L-shaped bracket plate, the opposite limb 20 terminating to provide a right angularly disposed flange, constituting 65 a fixed jaw 21. Coöperating with the jaw 21 is a relatively movable jaw 22 preferably consisting of a wooden block 23 slidably engaging the limb 20 of the plate, and having a metal binding strip 24 covering the exposed edges of the block and secured thereto in any suitable manner. The strip 24 terminates at both ends to provide hook-like portions 25 which embrace the opposite longitudinal edges of the limb 20 and serve 70 as a guide for the movable jaw in its adjustment toward and away from the fixed jaw 21. The movable jaw may be so adjusted in any suitable manner, however as shown in this particular instance use is made of a 80 screw 26 extended through a suitable opening in the limb 19 of the bracket plate, and adjustably associated with a fixed nut 27 secured to the under side of the limb, the screw having one end swiveled within the 85 block 23 and its opposite end provided with a knurled nut 28 for operating the screw in the proper direction to adjust the movable jaw toward and away from the fixed jaw 21 as the occasion may require. As shown in 90 this instance the arm is clamped upon the edge of the door A, although it is susceptible for use in other connections, it being manifest that by reason of the adjustment of the fixed jaw 22 the device may accommodate 95 itself to doors or the like of varying thickness.

Pivotedly secured to the under side of the base 16 is one end of a lever 29 which bridges a resilient finger 30, the latter also 100 having one end secured to the under side of the base 16 and its opposite end normally spaced from said base, and operatively associated with the adjacent end of the pintle 14. The lever is arranged to slide 105 in a suitable guide 31 which is constructed to limit the adjustment of the lever in one direction, while the opposite end of the lever projects beyond the bracket whereby it may be easily grasped to adjust the same when 110 desired. In the normal position of the lever 29 the latter is slightly spaced from the fin-

ger 30, in which position of parts the spring 18 operates to maintain the enlarged portion 17 of the pintle disposed in the path of movement of the arm 12 of the hammer, 5 thereby rendering the alarm mechanism inoperative. However the lever 29 is only used to render the alarm mechanism inoperative, when use of the alarm is not desired, as for instance during the day, it being 10 borne in mind that the device is primarily designed for use with a movable member such as a door or the like, and adapted to automatically operate to give a signal when such movable member is adjusted from its 15 normal position.

To carry this idea into effect use is made of an elongated member 32 slidably mounted upon the limb 19 of the bracket plate through a suitable guide 33, the member 32 extending 20 through an elongated slot in the base 16 and terminating to provide a flange 34 for engagement with the hammer arm 12. The opposite end of the member is also formed to provide a flange 35 adjacent which a slot 25 37 is provided. A leaf spring 36, passes through a transverse slot 37 in said member for a purpose to be presently described. The spring 36 is bowed outwardly and has its opposite end fixed in any suitable manner to the limb 20 of the bracket plate, and adapted to operate within a longitudinally disposed groove 38 formed in the limb 20. By reason of the manner in which the device in its entirety is mounted upon the door 30 as shown, it is manifest that as the door is swung to its closed position the spring 36 is brought into engagement with the door jamb B, and thereby straightened or moved into the groove 38. As the spring is straightened 35 it operates upon the member 32 to move the latter into effective engagement with the hammer arm 12, thereby holding the latter immovable and rendering the alarm mechanism inoperative. Of course when use of 40 the alarm mechanism is desired, and subsequent to the closing of the door, so that the parts will assume the position hereinabove mentioned, the lever 29 is moved toward the free end of the finger 30, engaging and depressing the latter, thereby adjusting the pintle 24 against the tension of the spring 18, and moving the enlarged portion 17 of the pintle out of the path of movement of the hammer arm 12, in which position of 45 parts the alarm mechanism is free to automatically operate upon opening of the door. Now as the door is opened, the spring 36 in assuming its normal position operates to retract the member 32, thereby moving the 50 latter out of engagement with the hammer arm 12 and liberating the alarm mechanism which instantaneously operates to sound the alarm.

In Figs. 5 and 6 we show a modified form 65 of the invention, which differs from the pre-

fferred form hereinabove described with regard to the means employed for holding the alarm mechanism inoperative when the door is in closed position. In this form of the invention use is made of a bracket plate 70 identical in construction with the plate hereinabove described, wherein the limb 39 of which is adapted to be secured in any suitable manner to the alarm indicated generally at A', while the limb 40 terminates to 75 provide a right angularly disposed flange constituting a fixed jaw 41. Slidably fitted upon the limb 40 is a relatively movable jaw 42, which is preferably operated by means of a screw 43 passing through the limb 39 80 and having one end swiveled in the jaw 42, the opposite end of the screw being provided with a knurled nut 44, whereby the screw may be rotated in a proper direction to move the jaw toward and away from the fixed 85 jaw 41 as the occasion may require.

The alarm mechanism in this form of the invention is exactly the same as that hereinabove described, and with a view of rendering the alarm mechanism inoperative when 90 the door is in closed position, I employ a member 45 pivoted upon the limb 39 of the bracket plate, and having one end terminating in a flange 46 for engagement with the hammer arm 12 of the alarm. The opposite end of the member 45 projects beyond the limb 39 at its point of juncture with the limb 40, and is provided with a transverse slot 47 which receives for association therewith one end of an operating element 48. 100 This element preferably consists of a flat arm slidably fitted upon the limb 40 and arranged to operate within a groove 49 in said limb whereby the element 48 will lie flush with the surface of the limb 40. Arranged within the groove is a headed stud 50 for the purpose of holding the element 48 in operative position with relation to its respective limb of the bracket, the element 48 being provided with the slot 51 for the 110 reception of said stud whereby the element is free to slide upon the limb. The free end of the operating element 48 terminates to provide a right angularly disposed flange 52 arranged in advance of the fixed jaw 41 for 115 the purpose to be presently described. The flange 52 is normally held in spaced relation to the fixed jaw 41 through the medium of a spring 53 bearing upon one end of the member 45, which spring also operates to 120 normally maintain the flange 46 of the member 45 elevated and out of engagement with the hammer arm 12 of the alarm mechanism, thereby permitting the alarm mechanism to operate to sound an alarm, except when the 125 alarm mechanism is rendered inoperative through the medium of the lever 29. However when use of the alarm is desired the lever 29 is moved to an inoperative position, subsequent to the closing of the door or the 130

like, whereupon the flange 52 of the operating element 48 is brought into engagement with the door stop 54 on the door jamb B, thereby sliding the operating element 48 upon the limb 40 in a direction whereby pivotal movement is imparted to the member 45 against the tension of the spring 53, thus bringing the flange 46 of said member into engagement with the hammer arm 12, 10 holding the latter immovable and rendering the alarm mechanism inoperative as long as the door is in its closed position. Now as the door is opened, the spring 53 operates to reverse the pivotal movement of the member 45, thereby elevating the flange 46 thereof out of engagement with the hammer arm, liberating the alarm mechanism which instantaneously operates to sound an alarm. Of course during this operation the operating element 48 is moved to normal position, or in other words the flange 52 thereof is again spaced from the fixed jaw 41. It will thus be noted that we have devised a device of the class in question which may be 25 quickly and easily fitted to any door, window or the like, and removed therefrom when desired, the device being both simple in construction and very efficient for the purpose intended.

30 While it is believed that from the foregoing description the nature and advantages of the invention will be readily apparent, we desire to have it understood that we do not

limit ourselves to this precise construction and arrangement of parts, and that various 35 changes may be resorted to when desired as fall within the scope of the appended claims.

What is claimed is:—

1. The combination with a door and jamb, of an alarm bell disposed upon the door and 40 embodying a vibratory striker, a plate movable into the path of travel of said striker, and a spring disposed upon the edge of the door and connected with said plate, the compression of said spring between the edge of 45 the door and the jamb urging said plate against said striker.

2. The combination with a door and jamb, of an alarm bell disposed upon the door and embodying a vibratory striker, a horizontally disposed plate guided for slidable movement within said bell to engage the striker, the outer end of said plate being apertured, and a flat spring disposed upon the edge of the door and resiliently 50 divergent therefrom and having its free end disposed within said aperture for normally retaining said plate out of the path of travel of said striker, the compression of said 55 spring toward the edge of the door by the jamb when the door is closed urging said plate into engagement with said striker.

In testimony whereof we affix our signatures.

WILLIAM D. MOTT.
LEWIS VAN BROWN.
